Primary Examiner — George D. Kirschbaum*Assistant Examiner* — Clesie Moore, Jr.(74) *Attorney, Agent, or Firm* — Michael J. Bootcheck,
LLC(57) **CLAIM**

The ornamental design for a hitch step, as shown and described.

DESCRIPTIONFIG. 1 is a perspective view of a hitch step;
FIG. 2 is an exploded view thereof;

FIG. 3 is a front view thereof;

FIG. 4 is a rear view thereof;

FIG. 5 is a first side view thereof;

FIG. 6 is a second side view thereof;

FIG. 7 is a top view thereof;

FIG. 8 is a bottom view thereof;

FIG. 9 is a side view thereof with the device in an upright collapsed condition; and,

FIG. 10 is a side view of the hitch step only showing the top step, with the collapsible steps removed for ease of illustration.

The broken lines shown illustrate portions of the hitch step that form no part of the claimed design.

1 Claim, 6 Drawing Sheets(56)
